UNITED STATES PATENT OFFICE

2,155,265

RAILWAY CAR END WALL

Garth G. Gilpin, Riverside, Ill., assignor, by
mesne assignments, to Standard Railway
Equipment Manufacturing Company, a corpora-
tion of Delaware

Application April 1, 1937, Serial No. 134,209

4 Claims. (Cl. 105—410)

The invention relates to end walls for railway cars which are made of metallic plates or sheets formed with a plurality of substantially parallel and sinuous corrugations to provide a plurality of beams extending between the opposite side walls of the car so as to transmit horizontal loads imposed thereon, such as caused by a shifting load, to the side walls of the car. Such a construction is generally shown in the patents to 5 Small, No. 1,681,811 and No. 1,681,812 of August 10, 1928.

The sinuous corrugations open up under stress like an accordion pleat, thereby giving resiliency to the end wall structure. This yielding causes 15 a bulging of the structure which pulls the corner posts of the car inwardly or toward each other, and as these corner posts are rigid frame members of the car, they are necessarily quite stiff, therefore, such inward deflection frequently gives them 20 a permanent set, thus preventing the bulged end from returning to normal position.

One of the objects of the invention is to provide flexible means between the usual corner posts of the car and the corrugated metallic end 25 wall so that when the corrugated end wall is deflected under a horizontal thrust, the means will flex or yield without disturbing or distorting the corner posts and furthermore so that the corrugated end wall will return to normal position 30 without permanently distorting any of the car parts associated therewith.

Another object is to attach such flexible means to parts of the car so that the relative flexibility of their middle and end portions is substantially 35 commensurate with amount of flexing caused by the relative amount of bulging of the corrugated end at the middle, top and bottom thereof.

In the drawings:

Fig. 1 shows the end of a railway box car 40 equipped with my improved device.

Fig. 2 is a section on line 2—2 of Fig. 1.

Fig. 3 is a section on line 3—3 of Fig. 1.

Fig. 4 is an enlarged section on line 4—4 of Fig. 1.

Figs. 5 to 11 inclusive show modified constructions.

The drawings show the usual Z bar corner posts 2 and side wall sheathing 3 and lining 4 which form a part of the side truss to carry part 50 of the weight of the lading and the car to the body bolsters and which also resist the lateral thrust of the lading when the side wall acts as a retaining wall, therefore, the posts must be very strong and rigid. Each post is secured to the side 55 plate 6 of the car and also the side sill 7 of the car.

An extension plate 10 is secured to each side wall, preferably to the corner post 2, and has a portion 11 extending beyond the corner post and in substantially the same plane as the side wall and provided with a return flange 12 portion. 5 The extension plate is preferably attached to the side plate 6 and side sill 7 of the car.

The metallic end wall 15 sheet is formed with a plurality of parallel corrugations 16 which extend to the opposite edges of the sheet. The edges of 10 the metallic end wall sheet abut the return flanges 12 of the extension plate and are secured thereto preferably by welding 17.

In this arrangement when the end wall deflects 15 outwardly the bend in the extension plate opens up or flexes and the portion of the extension plate also distorts, thus providing a resilient flexibility.

Under horizontal load the corrugations in the end wall will open up and allow the end wall to 20 deflect and the greatest deflection will occur substantially midway between the top and bottom of the end wall and consequently the yielding or the pull in of the extension plates will be greater substantially midway between their tops and bottoms than elsewhere. In other words, my 25 constructions allow the extension plates to yield commensurate with the yielding of the end wall. Furthermore, as the tops and bottoms of the extension plates are anchored they offer some 30 resistance to deflection thereof which tends to return the extension plates and the end wall to normal positions.

Fig. 5 shows an extension plate 30 extending substantially in the same plane as the side wall 3 to which the corrugated end wall 31 is secured. 35

Fig. 6 shows an extension plate 35 having a flange 36. The corrugated end wall 37 is welded to a flat end piece 38 which in turn is riveted 39 to the extension plate 35 under the flange 36. A plate formed with corrugations extending to the 40 opposite edges thereof is quite flexible so the end piece 38 holds it in shape while being attached to the extension plate.

Fig. 7 shows the extension plate 40 parallel to 45 and in contact with the end piece 41 and secured thereto by welding 42. These members may also be welded together at 43.

Fig. 8 shows the extension plate 45 formed with a corrugation 46 lengthwise of the extension plate 50 and having a flange 47 corrugated to register with the corrugations of the end wall sheet 48 and secured thereto 49.

Fig. 9 shows an extension plate 55 formed with a lengthwise corrugation 56 on the side of the 55

car and also a corrugated flange 57 fitting the corrugations of the end wall sheet 58.

Fig. 10 shows an extension plate 60 formed with an offset portion 61 and a shoulder 62 with the end wall sheet 63 secured to the offset portion 61.

Fig. 11 is similar to Fig. 10 but shows the extension plate 65 connected to the offset portion 66 by large radial portions 67. The end wall sheet 68 is attached to the offset portion 66.

In my copending application I have disclosed and broadly claimed means for flexibly attaching a corrugated end wall sheet to the side wall or corner posts of a railway car, whereas in this application I claim a modification thereof where-in the corrugations in the end wall sheet extend to the opposite vertical edges of the sheet, thus necessitating a different method of attaching the corrugated end wall sheet to the flexible extension plates.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a railway car having spaced apart corner posts and a side wall secured to each post in combination with a flexible extension plate secured to each side wall and having a portion extending therebeyond, and a metallic end wall sheet formed with a plurality of corrugations extending be-

tween the opposite edges of the sheet and secured to said portions of the flexible extension plate so that when the corrugated end sheet deflects under load the corner posts will not be distorted.

2. In a railway car having spaced apart corner posts and a side wall secured to each post in combination with a flexible extension plate secured to each side wall and having a portion extending therebeyond, said plate being bent to form a return flange, and a metallic sheet end wall formed with a plurality of corrugations extending between the opposite edges of the sheet and secured to said return flanges of the extension plates.

3. In a railway car having spaced apart corner posts and a side wall secured to each post in combination with a flexible extension plate secured to each side wall and having a portion extending therebeyond, each of said portions having a part offset from the plane of the side wall, and a metallic end wall sheet formed with a plurality of corrugations extending between the opposite edges of the sheet and secured to said offset parts of the flexible extension plate.

4. In a railway car having spaced apart corner posts and a side wall secured to each post in combination with a flexible extension plate secured to each side wall and having a portion extending therebeyond, a metallic end wall sheet formed with a plurality of corrugations extending between the opposite edges of the sheet, and a member abutting each end of the corrugations and secured thereto, said members being secured to said portions of the flexible extension plate.

GARTH G. GILPIN.
